UNITED STATES PATENT OFFICE

MALCOLM S. CATE, OF WALTHAM, MASSACHUSETTS, ASSIGNOR, BY MESNE ASSIGNMENTS, TO HOOD RUBBER COMPANY, INC., OF WILMINGTON, DELAWARE, A CORPORATION OF DELAWARE

HEEL TRIMMING MACHINE

Application filed August 16, 1929. Serial No. 386,389.

This invention relates to a machine for trimming the edges of rubber heels for boots and shoes.

In the molding of rubber heels the excess 5 rubber in the mold flows out at the top and bottom and forms a fin on the top and another on the bottom of the heel being molded.

It is the object of this invention to provide a machine which will automatically trim 10 the fin off of the lower edge of the heel and also off of the upper edge of the heel.

It is further an object of the invention to provide a machine in which the heels are automatically fed into the machine to a work 15 support on a carrier, which, in the embodiment of my invention hereinafter set forth, is a rotary carrier. This carrier is intermittently rotated to carry the heel, first, to a pair of rotary cutters which trim the fin off 20 of the bottom edge of the breast of the heel while the carrier is continuing its rotation, and second, the heel is carried to a second pair of rotary cutters where the fin is trimmed off the opposite sides of the heel and off 25 of the circular rear edge thereof. The intermittent motion of the carrier renders it possible for the heel to be rotated while the carrier stands still. The heel is then carried to another pair of cutters which trim the 30 fin from the upper edge of the breast, and finally is carried to another pair of cutters which trim the fin from the sides and rear portion of the upper edge of the heel. The carrier then carries the heel to a device which 35 ejects the heel from the machine and finally the carrier returns to its initial position in readiness to receive another heel. The carrier has a plurality of arms whereby a plurality of heels may be trimmed at the same 40 time.

To these ends the invention consists in a heel trimming machine of the character set forth in the following specification and particularly as pointed out in the claims.

Referring to the drawings:

Figure 1 is a plan view of a machine embodying my invention.

Fig. 2 is a detail plan view partly in section 50 of the drive mechanism for rotating the heel

when the circular rear portion thereof is being trimmed.

Fig. 3 is a front elevation of the mechanism for feeding the heels from a stack on to the work support. 55

Fig. 4 is a sectional elevation taken on line 4—4, Fig. 3, illustrating a portion of the feed mechanism.

Fig. 5 is a detail sectional elevation taken on line 5—5, Fig. 3. 60

Fig. 6 is a plan broken away showing the feed mechanism and a portion of the carrier and the means for positioning the heel with relation to the work support.

Fig. 7 is a side elevation viewed in the direction of the arrow *a*, Fig. 6, illustrating the work support and the means whereby the heel is clamped to the work support, together with a portion of the carrier, a portion of a heel being shown in section clamped 70 to the work support and a portion of a cam also shown in section. 65

Fig. 8 is a detail side elevation viewed in the direction of the arrow *b*, Fig. 6, illustrating a locking arm for holding the carrier 75 in a stationary position while the heel is being positioned thereon.

Fig. 9 is an elevation of the first pair of cutters and the mechanism for rotating them, viewed in the direction of the arrow *c*, Fig. 80 1, with a portion of the heel which is being trimmed shown in section and also a portion of the bed of the machine, the work support being shown broken away.

Fig. 10 is a sectional elevation taken on line 10—10, Fig. 9. 85

Fig. 11 is a side elevation of the gearing for imparting rotary motion to the cutters, viewed in the direction of the arrow *d*, Fig. 9. 90

Fig. 12 is a side elevation of the cutting mechanism of the second set of cutters, viewed in the direction of the arrow *e*, Fig. 1, the mechanism being similar to the mechanism illustrated in Fig. 9, except that a portion of the mechanism for rotating the work support and the heel thereon is illustrated. 95

Fig. 13 is a sectional plan taken on line 13—13, Fig. 12, illustrating the mechanism for rotating the work support. 100

Fig. 14 is a side elevation of the third set of cutters, viewed in the direction of the arrow *f*, Fig. 1, this view being similar to the view of the cutters illustrated in Fig. 9, except that the cutters are inclined at a different angle to the tread of the heel whereby the fin may be trimmed from the upper edge of the heel, whereas in Figs. 9 and 12 the fin is illustrated as being trimmed from the lower edge of the heel.

Fig. 15 is a detail elevation partly in section as viewed from the front of the machine, illustrating the ratchet and pawl mechanism for imparting an intermittent rotary movement to the carrier.

Fig. 16 is a detail sectional elevation taken on line 16—16, Fig. 7, illustrating the latch for holding the presser foot in position prior to clamping the heel to the work support.

Fig. 17 is a diagrammatic plan view illustrating the different positions of a heel as it is fed into and passes through the machine.

Fig. 18 is a side elevation and Fig. 19 an end elevation of a modified pair of cutters.

Like numerals refer to like parts throughout the several views of the drawings.

In the drawings, the heels 20 with the fins 21 and 22 thereon are piled in a stack as illustrated in Fig. 3 and are held in stack formation by vertical rods, or other suitable means not shown in the drawings but well known to those skilled in the art.

The lowermost heel 23 is shown in the drawings as resting upon a right-angled plate 24 which is fastened to a bracket 25 which is fastened to a feed slide 26, see Figs. 3 and 4. Immediately at the rear of the heel 23 is a pusher finger 27 and this is supported upon a slide 28 which is mounted to slide on ball bearings 29 in the bracket 25. Another plate 30 projects rearwardly from the stack of heels and is also fastened to the bracket 25. Thus it will be seen that by imparting a reciprocating motion to the slide 26, the pusher finger 27 will be moved forwardly together with the plates 24 and 30 so that the lowermost heel 23 will be pushed out from beneath the other heels 20 in the stack and the heel 23 carried forward into the machine to be placed on the work support as herein-after described.

When the slide 26 together with the bracket 25 returns after delivering the heel to the machine to the position illustrated in Fig. 3, the stack of heels 20 will drop when the plate 30 is moved to the extreme left and will then rest upon the plate 24, as illustrated in Fig. 3. The pusher being supported upon or fastened to the slide 28, which can slide laterally of the bracket 25, allows the heel 23 when fed into the machine to be centered between two guides and correctly positioned with relation to the heel support and presser foot.

The slide 26 is slidably mounted in ways 31 provided in a frame 32 and has a reciproca-

tory motion imparted thereto by an auxiliary slide 33, Figs. 3 and 4. The slide 33 has teeth thereon and embodies therein a rack 34 into which a gear 35 meshes. The gear 35 is fast to a vertical shaft 36 rotatably mounted in bearings 37 on a bracket 38 fast to the frame 32. To the lower end of the shaft 36 a pinion 39 is fastened to which a rocking motion is imparted by a segment gear 40 (Figs. 1 and 6) formed upon the outer end of a lever 41 which is pivotally mounted at 42 in the frame of the machine and has a rocking motion imparted thereto by a link 43 pivoted at one end at 44 to the lever 41 and at the other end to a crank pin 45 fast to a cam 46. The cam 46 is fast to a vertical shaft 47 and is driven by a pulley, gear, or other suitable mechanism not shown in the drawings.

The left hand end of the auxiliary slide 33 terminates in a cylindrical extension 48 which has nuts 49 in screw-threaded engagement therewith, and interposed between said nuts and a plate 50 is a spring 51, the plate 50 being fastened to the slide 26. Thus a reciprocating motion can be imparted to the rack slide 33 and through the spring 51 and nuts 49 and extension 48 to the slide 26 can be moved forwardly with a yielding pressure.

The heel 23 is fed forward over a work support 52 and beneath a presser foot 53 in a manner hereinbefore set forth, and is positioned relatively to the work support 52 and presser foot 53 by a pair of guide plates 54 and 55 which have inclined guiding faces 56 and 57, see Figs. 1 and 6. These guide plates 54 and 55 are adjustable toward and away from each other to accommodate different sized or shaped heels and are slidably mounted in a bracket 58 which is fastened to the top of the frame 32, see Figs. 3 and 6. The guide plates 54 and 55 have rack teeth 59 and 60 on their adjacent edges and between these racks is positioned a pinion 61 which is fastened to a shaft 62 which extends upwardly through the top of the bracket 58 and has fastened thereto an arm 63 with a clamp handle 64 fast thereto. The clamp handle 64 has screw-threaded engagement with a stud 65 which extends through the arm 63. A stationary clamp plate 66 is also fastened to the bracket 58 and its periphery extends between the arm 63 and the nut 67, so that by turning the handle 64 in the proper direction the arm 63 can be clamped to the plate 66 or unclamped therefrom and consequently, the pinion 61 can be locked in position, thus locking the guide plates 54 and 55 in any desired adjusted position.

When the heel 23 is fed forward between the work support 52 and the presser foot 53, it is positioned as to further forward movement by the guide plates 54 and 55 which bear against opposite sides thereof, and it is also positioned and held against said guides during the first portion of the retracting move-

ment of the feed slides 26 and 33 by a finger 68, see Figs. 1, 3, 4 and 6. This finger is mounted to rock upon a rod 69 which is fastened at one end to a bracket 70, which in turn is fastened to the frame 32. The rod 69 at its left hand end, Fig. 6, is provided with a collar 71 into which one end 72 of a torsional expansion spring 73 projects, the other end of the spring 73 engaging the finger 68. The finger 68 is fastened to a block 74, this block being mounted to rock upon the shaft 69 and forming in effect a portion of the finger 68, Fig. 4.

As illustrated in Fig. 4, the finger 68 is held in elevated position so that the heel 23 when being fed forward to the machine passes thereunder and the said finger is held in elevated position by a ball 75 which rests upon a cam-shaped plate 76, see Figs. 3, 4 and 6. This cam-shaped plate is stationary and is fastened to the bracket 70. The finger 68 is prevented from moving toward the right, Figs. 3 and 6, by a stop lever 77 which is pivoted at 78 to the bracket 70 and has a downwardly projecting arm 79 and a horizontally extending arm 80, the horizontally extending arm 80 having a notch 81 in its free end which engages a portion 82 of the block 74 and thus prevents the finger 68 from being moved toward the right, from the position illustrated in Fig. 3, until the heel 23 has been fed in the manner hereinbefore described by the pusher finger 27 and plate 24 to a position beyond the finger 68 or at the right thereof, Fig. 3, whereupon the lever 77 is rocked on its pivot in the direction of the arrow *g* by a stud 83 fast to the slide 33 and projecting laterally thereof into the path of the lower end of the arm 79 so as to engage the same, and rocking the lever 77 in the direction of the arrow *g* it will be seen that the block 74 and the finger 68 fast thereto will be freed from the arm 80 of the locking lever 77 and thus the finger 68 will be allowed to be forced toward the right, Figs. 3 and 6, by the spring 73. At the same time the finger 68 and the block 74 will be rocked in the direction of the arrow *h*, Fig. 4, by the torsional action of the spring 73 and thus bring the finger 68 downwardly until its hook-shaped outer end 84 projects into the recess 85 in the pusher finger 27 and engages the breast portion of the heel 23 holding the heel 23 in between the guide plates 54 and 55. Now the heel is correctly positioned relatively to the work support 52 and the presser foot 53.

The slides 33 and 26 are now in readiness to move toward the left, Fig. 3, which is done by the mechanism hereinbefore described, the lever 41 being rocked in the opposite direction from that in which it was previously rocked to secure this end. The plate 24 will therefore be withdrawn from beneath the heel 23 leaving the heel gripped between the

guide plates 54 and 55 and the finger 68 and at this time the presser foot 53 will descend, as hereinafter described, and grip the heel 23 between it and the work support. On the return movement of the slides 33 and 26 a tooth-shaped plate 86, which is fastened to the slide 33, see Figs. 3 and 4, engages the tooth 87, which projects downwardly from the block 74, and pushes the block 74 backwardly together with the finger 68. As the block 74 and the finger 68 are thus pushed backwardly or toward the left, Fig. 6, the ball 75 on the block 74 will ride up on the inclined upper edge 76' of the cam 76 and thus tip the block 74 and finger 68 into the elevated position illustrated in Fig. 4, thus causing the tooth 87 to pass out of engagement with the plate 86 and at the same time the horizontal arm 80 of the lever 77 will move upwardly and will engage the block 74 locking it against movement toward the right, Fig. 3, as illustrated in Fig. 3, the said lever 77 being moved upwardly to lock the finger 68 in its retracted position by a coil torsional spring 88.

The work support 52 is rotatably mounted in a bearing 89 on the outer end of an arm 90, see Fig. 7. To the lower end of the work support 52 is fastened an arm 90', see Figs. 7, 12 and 13, and on the outer end of the arm 90' is a roll 91 rotatably mounted on a pin 92 in said arm. The arm 90' is flattened off at 93 and has a tooth 94 projecting from its outer end.

There are three arms 90, 95 and 96 and a work support 52 is rotatably mounted on the outer end of each of these arms. The arms 90, 95 and 96 project radially from a hub 97, Figs. 1 and 15. This hub is rotatably mounted upon a stud 98 which is clamped by a nut 99 to a cylindrical bed plate 100. Upon the stud 98 is rotatably mounted a gear 101 to which an arm 102 is fastened, the outer end of said arm having a pawl 103 mounted to rock on a stud 104 which is fastened to the arm 102 and is held by a torsional spring 105 against a ratchet 106 which is fastened to the hub 97 of the carrier 107, said carrier consisting of arms 90, 95 and 96 and the hub 97. A segmental gear 188, as hereinafter described, will impart a rocking movement to the gear 101 and thus a rocking movement will be imparted to the arm 102, and the pawl 103 engaging teeth on the ratchet 106 will impart an intermittent rotary movement to the ratchet 106 and to the carrier 107 with its arms 90, 95 and 96, thus carrying the heels to the different cutting mechanisms A, B, C and D, Fig. 1.

A plate 108 is fastened to the upper end of each of the work supports 52 and these plates are provided with prongs 109 which stick into one face of the heel 23 and the heel is held firmly pressed against the plate 108 by a clamp plate 110 rotatably supported on an arm 111, comprising as a whole the presser

foot 53. The arm 111 is fastened to a vertical rod 112 which is slidably mounted in a bracket 113 fast to the arm 90.

The work support and presser foot are duplicated on each of the arms 90, 95 and 96, therefore a description of one of these devices will apply to all three.

A spring 114 encircles the rod 112 and acts to force the presser foot 53 downwardly. It 10 is held upwardly against this downward pressure by a latch 115, Fig. 16, which is provided with two teeth 116 and 117. The latch 115 is pivoted to a stud 118 which is fastened to the lower end of the rod 112 and 15 projects laterally therefrom, see Fig. 7. The latch 115 is provided with a lateral projection 119 which, as the cam 46 is rotated in the direction of the arrow *i*, Fig. 6, is rocked to rock the latch 115 to disengage the tooth 117 20 from engagement with a plate 120 fast to the arm 90. Disengaging of the tooth 117 from the plate 120 allows the spring 114 to act to press the rod 112 downwardly and to press the presser foot plate 110 against the heel 23, thus forcing it on to the prongs 109 on the work support 52.

The latch 115 is rocked in the manner hereinbefore set forth by a lever 121, Figs. 6 and 7, which is pivoted at 122 to a plate 123 which, in turn, is pivoted to a stud 124 fast to the cylindrical bed plate 100, and the plate 123 is rocked upon the pivot 124 by a cam projection 125 projecting from the periphery of the cam 46, and as said cam is rotated in the direction of the arrow *i*, Fig. 6, this projection engages a roll 126 mounted on a stud 127 fast to the plate 123 and projecting downwardly therefrom, see Fig. 7. The lever 121 is held normally in the position illustrated in Fig. 7 by a spring 128, one end of which is fastened to the lower end of said lever 121, the other end being fastened to the stud 127.

The carrier, during the clamping of the heel to the presser foot, is locked in position by an arm 129, see Fig. 6, which is pivoted to a stationary stud 130 fast to the bed plate 100. This arm is held normally against a stop screw 131 by a torsional spring 132 and it has an upwardly extending plate 133 fast thereto, and having in one edge thereof a notch 134 which engages a locking plate 135 fast to the arm 90. One of these locking plates 135 is provided upon each of the arms 90, 95 and 96. The plate 129 is provided with a cam roll 136 rotatably mounted thereon and adapted to engage a cam groove 137 on the periphery of the cam 46. As shown in Fig. 6 the arm 90 is locked by the arm 129 as the locking plate 135 is projecting into the notch 134 on the plate 133.

As the cam 46 rotates in the direction of the arrow *i*, it will be evident that as the roll 136 rides out of the cam groove 137 the arm 129 will be rocked in the direction of the

arrow *k*, Fig. 6, and the locking plate 135 will be disengaged from the arm 133. Now the carrier 107 will be free to be rotated by the pawl and ratchet mechanism, hereinbefore described, carrying the heel 23 from the position *x*, Fig. 17, to the position *w*, where its breast portion is brought into engagement with an arcuate guide plate 138, Fig. 1, of substantially the same radius, and upon continued rotation of the carrier 107 the heel is swept along said guide plate past a pair of rotary cutters 139 and 140. These cutters are fast to rotary shafts 141 and 142 parallel to each other and rotatably mounted in bearings 143 and 144, see Figs. 9 to 11 inclusive respectively. The shaft 141 has a spiral gear 145 fast thereto. The shaft 142 has a spiral gear 146 fast thereto, and these two spiral gears mesh into other spiral gears 147 and 148 respectively. The gears 147 and 148 have their teeth reversely inclined, so that they rotate the shafts 141 and 142 in opposite directions relatively to each other. The gears 147 and 148 are fastened to a rotary shaft 149 to which rotary motion is imparted by a flexible shaft 150 rotated by gear mechanism 151 to which motion is imparted by a pulley 152, Fig. 1.

In order to adjust the shafts 141 and 142 toward or away from each other, the bearings 143 and 144 are slidably mounted in a bracket 153 and have screw-threaded engagement with a screw 154 which is screw threaded at 155 and 156 to engage nuts 157 and 158 respectively, these nuts being positioned in slots 159 and 160 in the bearings 143 and 144, and the screw threads 155 and 156 are reversely inclined, so that by rotating the screw 154 the bearings may be drawn toward each other or moved apart. The screw 154 is rotatably mounted in another screw 161 which has screw-threaded engagement with the bracket 153, so that by rotating the screw 161 both of the bearings 143 and 144 may be simultaneously adjusted to change the relative location of the cutters 139 and 140 to the face of the heel 23. The bracket 153 also supports the guide plate 138.

It will be noted that the axes of the cutter shafts 141 and 142 are inclined at an angle to the tread of the heel 23 and as shown in Fig. 9 the fin 21 on the heel 23 is brought into engagement with the cutters and separated therefrom, this being the fin on the lower edge of the breast of the heel.

The cutters 139 and 140 are held in engagement with the lower edge of the heel 23 by reason of the fact that the bracket 153 is moved toward the heel by a spring 162, one end of which is fastened to a plate 163 fast to a stationary bracket 164 which, in turn, is fastened to the stationary bed plate 100. The bracket 153 is slidably mounted in ways 165 on the upper end of the bracket 164 and

the spring 162 is fastened at its outer end to an arm 166 which is fastened to the bracket 153. A stop 167 is provided to limit the distance to which the cutter bracket 153 can be moved inwardly or toward the center of the bed plate 100.

The arrangement is such that as the carrier 107 sweeps the breast portion of the heel along the guide plate 138 past the cutters 139, 140, the cutter mechanism as a whole is forced rearwardly against the tension of the spring 162. The heel is thereby turned from position *w* to position *v* (see Fig. 17), since the holder 52 is free to turn pivotally at position A.

The fin having now been trimmed from the lower edge of the breast of the heel, the heel is next carried to the cutter mechanism B, Figs. 17, 12 and 13. These cutters remove the lower fin from the opposite sides of the heel and from the circular rear end portion of the heel, and the heel is brought to the cutters from the position *v*, Fig. 17 to the position *u*. It is turned from the position *v* to the position *u* by the combined action of the guide plates 168 and 169, Fig. 1. The guide plate 168 is engaged by the roll 91 on the arm 90', which is fastened to the work support 52, so that as this roll is rocked by engagement with the guide plate 168 it turns the work support 52 into the proper position for one side *u'* of the heel 23, see Fig. 17, to be properly positioned by the coaction of the roll 91 with the guide plate 168 and the coaction of the side of the heel with the plate 169 to properly position the heel to be engaged by the cutters 170 and 171 of the cutter mechanism B.

It is unnecessary to enter into a detailed description of the mechanism by which the cutters 170 and 171 are rotated as it is the same as the mechanism whereby the cutters 139 and 140 are rotated. The only difference between the two cutter mechanism A and B is that the guide plate 169 is of different shape than the guide plate 138 and the bracket 153 is slidably mounted on a slide frame 172 so as to slide toward the heel, and the slide frame 172 is slidably mounted in ways 173 on a bracket 174 fast to the bed plate 100, so that the cutters 170 and 171 are urged toward the heel by the spring 162 and they are moved tangentially relatively to the heel by the slide 172, and this tangential motion is imparted by mechanism hereinafter described.

Referring now to Fig. 17. The heel is moved from the position *u* by the motion of the carrier 107 in the direction of the arrow *m*. The carrier then comes to a stop and the heel is given a half rotation by the work support 52, as illustrated in Figs. 12 and 13, and the work support 52 is rotated by a gear 175 which is fast to a shaft 176 rotatably mounted in a bearing 177 in a bracket 178 fast to the bed of the machine. The upper end of the

shaft 176 is flattened off transversely thereof at 179 and the flattened surface 179 engages the flattened surface 93 on the arm 90', so that when the gear 175 is rotated a half rotation a like rotation will be imparted to the arm 90' and to the work support 52 to which it is fastened, thereby imparting a half rotation to the heel 23. Although the shaft 176 is so positioned in the orbit of the arm 90' that its flattened portion 179 engages the flattened portion 93 of said arm, the half rotation of the shaft 176 reverses the positions of the flattened members so that the arm 90' is free to move away from the shaft 176 upon continued movement of the carrier 107.

The gear 175 is rotated by a rack 180, Figs. 1 and 2, with which it is in mesh and the rack 180 is fastened to a slide 180' slidably mounted in ways 181 on the bed plate of the machine and has a reciprocatory motion imparted thereto by a gear 182 which meshes with a rack 182' on the slide 180'. The gear 182 is rocked by a segment gear 183 on a lever 184 which is pivoted to a stud 185 on the bed plate of the machine and is rocked by a cam roll 186 which engages a cam path 187 in the cam member 46. This lever 184 also imparts a rocking movement to the gear 101 by means of a segment 188 forming a portion thereof, which meshes with the gear 101 and thus imparts an intermittent rotary movement to the carrier, as hereinbefore described, through the pawl and ratchet mechanism.

When the fin is being trimmed from the circular rear portion of the heel a rotary motion must be imparted to the heel and at the same time a tangential motion imparted to the cutters relatively to the edge of the heel for the reason that the contour of the rear portion of the heel is not an exact circle and this combined rotary movement of the heel and tangential movement of the cutters relatively to the heel is obtained by rotating the heel, as hereinbefore set forth, and at the same time moving the cutters tangentially relatively to the heel by sliding the bracket 172 in a direction transversely to the axes of the cutters 170 and 171. This bodily tangential movement of the cutters relatively to the heel is obtained by means of a mechanism hereinafter to be described.

When the heel has been trimmed on the side *u'* and on the circular rear portion, the opposite side of the heel from the side *u'* is trimmed by the movement of the heel through its carrier and work support in the general direction of the arrow *m* until the heel arrives at the position *t*, Fig. 17. The heel is now moved by the carrier to the cutter mechanism C and this mechanism is substantially the same as the cutter mechanism A except that the cutters 189 and 190 are inclined at a different angle to the tread of the heel, so that they may be engaged by the upper edge

of the heel and trim the fin from the said upper edge, Figs. 1 and 14.

The bracket 153', upon which the cutter shafts are rotatably mounted, is adjusted vertically to bring the cutters to the proper height relatively to the upper face of the heel by means of a rack 191 which is fastened to the bracket 153' and is slidably mounted upon a bracket 192 which is fastened to a slide 193 slidably mounted in ways 194 on a bracket 195 fast to the bed plate 100. The bracket 153' is moved upwardly or downwardly for the purpose specified by means of a pinion 196 and locked in position by a clamp handle 197 and plate 198, similar to the construction hereinbefore described, whereby the guide plates 54 and 55 are adjusted and locked in position. The cutters 189 and 190 are urged toward the breast portion of the heel by means of a spring 199, the same as in the form of cutter mechanism A. The operation of trimming the heel along the breast and on the upper edge is the same otherwise as that described in relation to the operation of the cutter mechanism A.

After trimming the upper edge of the breast of the heel, the heel is carried to the cutter mechanism D, which is substantially the same as the cutter mechanism B and operates in substantially the same manner except that the cutters are inclined as in the cutter mechanism C and the vertical adjustment of the cutters relatively to the heel is the same as in the cutter mechanism C. The cutter mechanism D has a transversely movable slide frame 172' to impart the tangential movement of the cutters relatively to the heel while the circular rear portion of the heel is being trimmed, and a reciprocatory motion is imparted to this slide frame 172' by a lever 200 which is pivoted at 201 to the bed plate of the machine and has a rocking motion imparted thereto by a cam roll 202 positioned in a cam path 203 in the top of the cam member 46. This rocking motion is conveyed from the lever 200 to the slide frame 172' by a bracket 204 which is fastened thereto and is provided with a stud 205 which projects downwardly therefrom into a slot 206 in the lever 200. The stud 205 is adjustable longitudinally of the slot 206 in order that different throws may be imparted to the slide frame 172'. The slide frame 172' is connected by a link 207 to a bell-crank lever 208 which is pivoted at 209 to the bed plate of the machine and is connected by another link 210 to the slide frame 172 of the cutter mechanism B. The link 210 by a turn-buckle construction is rendered adjustable longitudinally thereof in order to initially position the slide frame 172.

In the cutter mechanism D the work support 52 is rotated in the same manner as in the cutter mechanism B except that the arm 90' and the work support to which it is

attached are rotated by a gear 211, Fig. 2, instead by the gear 175. The gear 211 is rotated by a rack 212 fast to the slide 180'.

As the heel 23 is carried from the cutter mechanism B to the cutter mechanism C the roll 91 engages a cam plate 213 and this rocks the arm 90' and the work support 52 and brings the heel into approximately the position *s*, Fig. 17, in readiness to engage the guide plate 138' in the cutter mechanism C, and as the heel is carried to the cutter mechanism D the roll 91 engages the cam plate 168' and the heel engages the guide plate 169', whereby the heel is guided to the position *r* from the position *s*', which it assumes as it leaves the guide plate 138'. (See Figs. 1 and 17.)

As the heel is being trimmed by the cutter mechanism D, which as stated is substantially like the cutter mechanism B, it is positioned and manipulated and trimmed in the same manner as by the cutter mechanism B, except that the upper edge of the heel is being trimmed instead of the lower and the heel passes through the three different positions shown in Fig. 17 while being operated upon by the cutters D, that is, the positions *r*, *p* and *o*.

The fins having been now trimmed from the edges of the upper and lower faces of the heel the heel is carried forward by the carrier 107 from the position *o* to the position *n* and in passing from the position *o* to the position *n* the presser foot 53 is lifted out of engagement with the heel 23 by a cam 214 which is shown in Fig. 1 and also in dotted lines in Fig. 7. This cam engages a roll 215 which is rotatably mounted on the stud 118. The roll is moved upwardly by the cam 214 and this moves the rod 112 upwardly thus raising the presser foot 53 out of engagement with the heel 23 and at the same time the latch 115 is raised, the same being mounted upon the stud 118, until the tooth 117 on said latch is raised above the top of the plate 120, whereupon a flat spring 216 rocks the latch 115 until the tooth 117 engages the upper face of the plate 120 which holds the latch against downward movement of the rod 112 and the presser foot.

The heel now rests upon the work support without any pressure thereon and is free to be stripped from the work support, which is done by the stationary stripper plate 217, Fig. 1. The heel after being stripped from the work support falls upon an inclined chute 218 and slides down said chute and into a suitable receptacle.

Upon continued movement by the carrier 107 the work support is now brought in position to receive another heel, that is, to the position illustrated in Fig. 1, and as the carrier moves to this position the roll 91 first engages the cam face 219 of a cam plate 220 and subsequently enters a cam path 221

formed upon said cam plate 220. When the carrier comes to a stop as illustrated in Fig. 1, it is therefore ready to have another heel fed to it in the position *x*, Fig. 17, as hereinbefore described in relation to the positioning of the heel 23. As the carrier approaches the position where a new heel is fed to the presser foot, the locking plate 135 engage the rounded end of the plate 133 and pushes it to one side against the action of the spring 132 and when the arm of the carrier frame arrives in the position illustrated in Figs. 1 and 6 the plate 133 is moved backwardly by the spring 132 so that the locking plate 135 enters the notch 134 and the carrier is thus locked against movement during the feeding of the heel and clamping of the same preparatory to another intermittent rotary movement.

During the different movements and operations hereinbefore described, and especially while the work support is being rocked to bring the heel into the correct position with relation to the cutters, as for example, in passing from the cutter mechanism A to the cutter mechanism B, or from the cutter mechanism B to the cutter mechanism C, or from the cutter mechanism C to the cutter mechanism D, there is a possibility of the arm 90' and work support being rocked accidentally by jarring or the like to assume undesirable positions and to guard against this eventuality a pair of detents 222 and 223 are provided, Fig. 6. These detents are pivoted at 224 and at 225 respectively to a cross bar 226 which is fastened to the underside of the arm 90. A spring 227 is connected at its opposite ends to the detents 222 and 223 and draws them toward each other until the inner edges of said detents engage flattened surfaces 228 and 229 on the cross bar 226. This construction limits the distance to which the detents 222 and 223 can be drawn toward each other and positions them with relation to the roll 91 and the arm 90' upon which it is mounted as well as the work support 52 to which the arm 90' is fastened. If there is any tendency for the arm 90' and parts connected thereto to be accidentally moved out of position, as hereinbefore set forth, the arm 90' will engage the inner edge 230 of the detent 223 which will apply frictional resistance to the rotation of the arm 90' in a clockwise direction, Fig. 6, and if the arm 90' is swinging around in the opposite direction, or in a counterclockwise direction, the tooth 94 thereon will engage a tooth 231 on the detent 222 and this will lock the arm against further motion in a counterclockwise direction.

As the carrier is brought into position to have a new heel fed thereto the lateral projection 119 on the latch 115 will engage the bevelled surface 232 on the lever 121 and the lever will be rocked toward the right, Fig. 6,

until said lateral projection passes by, when said lever will be brought again to the position illustrated in Fig. 6 by the action of the spring 129.

The slide 28 has a recess 235 in its underside having oppositely inclined faces, and a ball 236 is positioned in a hole 237 in the bracket 25. A spring 238 holds the ball upwardly in the recess 235. If when the heel 23 is brought forward to engage the guide plates 54 and 55, it should engage one of the plates and not the other, the slide 28 would move in one direction or the other so that the heel would contact with both of said guide plates, and when the bracket 25 is retracted the ball 236 and spring 238 would operate to return the slide 28 to its normal position.

The general operation of the mechanism hereinbefore specifically and to a large extent in general described is as follows:—

The lowermost heel 23 in a stack of heels is fed by the mechanism illustrated in Figs. 3 and 6 from the position *y*, Fig. 17, to the position *x*. The heel is fed between a work support 52 and a presser foot 53 on one of the arms 90, 95 or 96, according to the position of the carrier 107. The heel is positioned by the feed mechanism with its rounded portion bearing against the plates 54 and 55 and is held in that position by the finger 68 which bears against the breast of the heel and is brought to bear against the breast of the heel by the mechanism hereinbefore described and illustrated in Figs. 3, 4 and 6. The carrier 107 is at this time locked in position by the mechanism hereinbefore described and after the heel is positioned and clamped to the work support by the presser foot, the carrier arm is unlocked, the carrier is rotated by the pawl and ratchet mechanism illustrated in Figs. 1 and 3 to the position *w*, the positioning of the heel being assisted by the guide plate 138 of cutter mechanism A. The cutter mechanism A trims the fin from the lower edge of the breast of the heel.

The heel is carried forward by the carrier 107 to the position *u* and is carried through the three different positions illustrated in Fig. 17, where the heel is trimmed on the opposite sides and around the circular portion. The heel is then carried to the position *s* and *s'* where the fin is trimmed from the upper edge of the breast of the heel by the cutter mechanism C.

The heel is then carried to the positions illustrated in connection with the cutter mechanism D, that is, *r*, *p*, and *o*, and the fin is trimmed from its upper edge on the opposite sides and the circular rear portion of the heel. The heel is then carried to the position *n* where it is removed from the machine and the carrier then moves to the position to receive another heel in the position *x*, Fig. 17.

Since the breast of the heel is trimmed by being swept past the cutting mechanisms A

and C, and the heel is removed from the machine by the movement of the work-support past the stationary stripper plate 217, it will be obvious that the carrier 107 is so indexed 5 that pauses in its movement occur only when the work-supports 52 are at the loading station, and trimming stations B and D.

While in the foregoing specification and in the drawings the cutters have been illustrated 10 and described as a pair of rotary cutters, and while this is the style of cutters which it is preferable to employ, still a pair of cutters such as illustrated in Figs. 18 and 19 may be utilized without departing from the spirit of 15 my invention.

Referring to Figs. 18 and 19, 233 is a rotary cutter and 234 a stationary cutter coacting therewith. These cutters when employed in the position of the cutter mechanisms A 20 and B will be tipped at an angle to trimming the fin from the lower edge of the heel as illustrated in Fig. 12, and when taking the place of the cutter mechanisms C and D the cutters 233 and 234 will be tipped to trim the 25 fin from the upper edge of the heel as illustrated in Fig. 14.

I claim:

1. In a heel trimming machine the combination of a trimming mechanism, a pivotally mounted work holder adapted to receive a shoe heel to be conveyed step by step to the trimming mechanism, and means for turning the work holder on its pivot during a pause of the work holder at the trimming 35 mechanism.

2. A machine as defined in claim 1 including automatic means for mounting the heel upon the work holder.

3. In a heel trimming machine the combination of a series of trimmer units, a work holder adapted to receive a shoe heel and convey it successively to the several trimmer units, and means for turning the heel on the work holder so as to cooperate with particular trimmer units in the trimming of the heel. 45

4. A machine as defined in claim 3 in which the movement of the work holder is intermittent and the work is turned thereon during 50 a pause in its movement.

5. In a heel trimming machine the combination of a series of trimmer units, a work holder adapted to receive a shoe heel and convey it step by step successively to said trimmer units to be partly trimmed thereby during a pause in the movement of the work holder, and a series of trimmer units positioned intermediate the units of the first mentioned series adapted to trim portions 55 of the heel as it is carried from one to another of said first-mentioned units.

6. In a heel trimming machine the combination of a trimming mechanism movable as a unit, a work holder adapted to receive 60 a shoe heel and convey it step by step to said

trimming mechanism, means for trimming the heel on the work support in timed relation to the movement of trimming mechanism, and means for coordinating the movements of the trimming mechanism and the 70 work holder to effect the trimming of a margin of the heel.

7. In a heel trimming machine, the combination of a pair of spaced apart trimming units, work holding mechanism adapted to 75 sweep the heel past the first trimming unit to remove the fin from the breast of said heel, and to carry the heel toward the second trimming unit, and means anterior to said second unit for turning the heel so that an untrimmed margin of the heel is presented to the latter.

8. In a heel trimming machine the combination of a pair of spaced apart trimming units, a work carrier adapted to sweep a heel past the first trimming unit to remove the fin from the breast of the heel, and to convey the heel to the second trimming unit, and means for turning the heel upon the carrier device while it is in engagement with the second 90 trimming unit to trim another margin of the heel.

9. A heel trimming machine as defined in claim 8 including means for causing the work carrier to dwell while the work is turned 95 thereon at the second trimmer unit.

10. In a heel trimming machine the combination of a cutter, a work holder adapted to convey a shoe heel in a fixed course past the cutter, and guiding means associated with the 100 cutter adapted to engage the breast of the heel to guide the latter into engagement with the cutter.

11. A heel trimming machine as defined in claim 10 including a yielding support for the 105 cutter.

12. In a heel trimming machine the combination of a cutter, a carrier moving in a fixed course past the cutter, and a work holder pivotally mounted for planetary movement on said carrier. 110

13. In a heel trimming machine the combination of a cutter, a carrier moving in a fixed course past the cutter, a work holder pivotally mounted upon the carrier and adapted to support a shoe heel, and guide means associated with the cutter adapted to effect feeding of the breast of the heel past the cutter in a course parallel to the breast of the heel. 115

14. A heel trimming mechanism as defined in claim 13 including a yielding mounting for the cutter.

15. In a trimming machine the combination of a rotatable work holder, means for securing a shoe heel thereto in a position intersected by the axis thereof, means engaging the work holder to rotate the same upon its axis, and a rotary cutter mechanism mounted for movement relatively to the heel 120

130

for trimming a portion of the heel as it is rotated by the work holder.

16. In a trimming machine the combination of a rotatable work holder, means for securing a shoe heel thereto upon the axis thereof, means for imparting determinate rotative movement to the work support to turn the shoe heel thereon, a cutter normally yieldingly urged toward the shoe heel, and means for moving the cutter transversely of the direction of its yielding movement.

17. In a trimming machine the combination of a plurality of trimming devices, a carrier, a work holder swiveled thereon, means for advancing the carrier step by step with pauses only at alternate trimming devices, and means for imparting determinate rotative movement to the work holder during the pauses of the carrier while permitting said work holder freely to turn while the carrier is in motion.

18. In a trimming machine the combination of a carrier adapted to be moved step by step, a work holder mounted for rotary movement on said carrier, a trimming device normally urged toward the carrier and adapted to be moved in a direction transverse to said normal urge, and means for indexing said carrier, rotating the work support thereon, and effecting transverse movement of the trimming device in determinate timed sequence.

In testimony whereof I have hereunto set my hand.

35 MALCOLM S. CATE.
